UNITED STATES PATENT OFFICE.

MATILDA STAFFORD, OF URBANDALE, IOWA.

DESIGN FOR A PIE-HOLDER.

50,852.

Specification for Design.

Patented May 29, 1917.

Application filed November 26, 1915. Serial No. 63,679. Term of patent 3½ years.

To all whom it may concern:

Be it known that I, MATILDA STAFFORD, a citizen of the United States, and residing at Urbandale, in the county of Polk and State of Iowa, have invented a new, original, and ornamental Design for a Pie-Holder, of which the following is a specification, reference being had to the accompanying drawing, forming part thereof.

I claim:

The ornamental design for a pie holder, as shown.

Des Moines, Iowa, October 19, 1915.

MATILDA STAFFORD.
